UNITED STATES PATENT OFFICE.

CARL BAUER, OF CHICAGO, ILLINOIS, ASSIGNOR TO DOETSCH & BAUER COMPANY, OF CHICAGO, ILLINOIS, A CORPORATION OF ILLINOIS.

DESIGN FOR A LEG OF A CHAIR OR SETTEE.

Application filed December 24, 1927. Serial No. 24,633. Term of patent 3½ years.

To all whom it may concern:

Be it known that I, CARL BAUER, a citizen of the United States, residing at Chicago, in the county of Cook and State of Illinois, have invented a new, original, and ornamental design for a Leg of a Chair or Settee, of which the following is a specification, reference being had to the accompanying drawing, forming part thereof.

Fig. 1 and Fig. 2 are respectively side and front views of the chair or settee leg showing my new design.

I claim:

The ornamental design for a leg of a chair or settee as shown.

In witness whereof, I hereunto subscribe my name, this 21st day of December, 1927.

CARL BAUER.
